[57] CLAIM

The ornamental design for a combined perfume bottle and closure, as shown and described.

DESCRIPTION

FIG. 1 is a front elevational view of a perfume bottle and closure showing my new design;

FIG. 2 is a rear view thereof;

FIG. 3 is a left side elevational view thereof;

FIG. 4 is a top plan view of the perfume bottle shown without the closure for clarity of illustration;

FIG. 5 is a bottom plan view of FIG. 4; and

FIG. 6 is a top plan view of the closure shown separately for clarity of illustration.
